COMBINATION SWITCH AND LIGHT
CONTROL FOR FLOOR LAMPS

Leslie N. Mattson, Paulsboro, N. J.

Application May 4, 1944, Serial No. 534,138

2 Claims. (Cl. 240—123)

1

The invention relates to an electric lamp, and more especially to a combination switch and light control for floor lamps.

The primary object of the invention is the provision of a control of this character, wherein it is only necessary to turn the shade of the lamp of the electric lamp for turning on or off the same, thereby eliminating the necessity of looking or feeling for the usual lamp switch, particularly when in the dark, the intensity of the light being readily controlled simultaneously when turning on the light.

Another object of the invention is the provision of a control of this character, wherein the same is unique and compact, and avoids the use of a button or snap-lever switch for service in turning on or off the light.

A further object of the invention is the provision of a control of this character, which is simple in its construction, thoroughly reliable and efficient in operation, neat in appearance, thus will not detract from the pleasing appearance of the lamp when a part thereof strong, durable, possessing few parts, susceptible of being easily repaired should the control get out of order, and inexpensive to manufacture and install.

With these and other objects in view the invention consists in the features of construction, combination and arrangement of parts as will be hereinafter described in detail, illustrated in the accompanying drawing, and pointed out in the claims hereunto appended.

In the accompanying drawing:

Figure 1 is an elevation partly in section of an electric lamp with the control constructed in accordance with the invention applied.

Figure 2 is a top plan view thereof.

Figure 3 is a horizontal sectional view through the rheostat of the control.

Figure 4 is an enlarged vertical sectional view through the control.

Similar reference characters indicate corresponding parts throughout the several views in the drawing.

Referring to the drawing in detail A designates generally the lamp standard of the electric floor type, and B the shade therefor.

The standard A at its upper end is formed with a cylindrical shaped hollow head 10 in the form of a crown and this head is fitted with bulb sockets 11, while the removable cover 12 for the said head is provided with a central opening 12' to receive the flat insulating disc 24 which is provided with an upstanding journal stud 13 for the turning axis for a hub 14 of a lamp shade

2

frame 15 of the shade B, the hub 14 being fixed to the arms 16 of the said frame 15. The hub 14 is retained on the stud 13 by a screw 17 and washer 18, respectively.

Stationarily mounted within the head 10 is an insulating base 19 for the resistance coil 20 with which contact is made by a flat rotatable contact 21 engaged on a pivot 22 centrally fitted at 23 to the base 19, the pivot 22 being threadedly received in the sleeve or hub 24' of the disc 24 in the cover 12, the disc 24 being of a smaller diameter than the central opening 12' forms an annular space 25 for accommodating the insulated L-shaped member 26 attached to contact 21. The member 26 travels in the annular space 25 and its forked upper end saddles an arm 16 of the frame 15 of the shade B, so that when the latter is turned clockwise or counter clockwise the contact 21 which has one end thereof engaging the resistance coil 20 will be similarly moved.

The coil 20 and the contact 21 are terminally connected electrically in a current supply circuit 27 of a house wiring line (not shown) which delivers current to the bulb sockets 11 for illumination of the lamp bulbs 28 as usual, the coil and contact, 20 and 21 intercept the circuit to the sockets 11, for the turning on and off of the bulbs 28. The base 19 is provided with stops 29 and 30, respectively, and when the contact 21 engages the stop 29 the circuit 27 is open, yet when the said contact 21 engages the stop 30 the circuit remains closed, the latter being constantly closed while the contact 21 traverses the coil 20, and according to the position of such contact 21 thereon the intensity of the light is increased or decreased. When the contact 21 is moved counter clockwise the same engages the stop 29 and on moving the contact 21 clockwise the stop 30 is engaged thereby.

The shade B completes the movement of the contact 21 and it should be obvious from the foregoing taken in connection with the drawing that the bulbs 28 are lighted and extinguished by turning the said shade B, and also the intensity of the light is regulated thereby.

What is claimed is:

1. In an electric lamp including a pedestal, an enlarged upper end on said pedestal, a lamp shade having a rotating frame on said pedestal, a resistance coil mounted on a circular insulating base secured to occupy a stationary position in the enlarged upper end of the pedestal of the lamp, a contact rotatably mounted in the upper

3

end of the pedestal contacting said resistance and adapted for operation through the medium of the frame of the lamp shade, a source of current connected to said resistance, a lamp bulb connected to said contact, and an L-shaped insulated member secured to said contact having the upper end thereof forked to provide an oper-

4

ative connection between said contact and the frame of said shade.

2. The invention as described in claim 1 wherein stops are provided at one end of the resistance coil for limiting the movement of the contact in both directions.

LESLIE N. MATTSON.
